W. C. Kniffin

Washing Machine.

Patented Dec. 17, 1834.

Dec. 17, 1834

William C. Kniffin Alexander, Genesee County, New York.

Seth's Patent

The Schedule referred to in this Seth's Patent and making part of the same contains
ing a description in the words of the said William C. Kniffin himself of his improvement
in the application of Gear Power to a Machine for washing Clothes or Cloth.

Wall to whom these presents shall come. Be it known, that I William C. Kniffin of
Alexander in the County of Genesee and State of New York have invented a
new and useful Improvement in the application of Gear Power to a Machine for
washing Clothes or Cloth, and that the following is a full & exact description
of the construction & operation of said Machine as invented by me.

The Machine consists of a square frame 12 to 18 inches high & 18
x 24 inches square, the posts of hard wood, of not less than two inches diameter, and the
horizontal pieces to connect them of hard wood and sufficient size to render the frame
strong and durable. Upon the frame and firmly attached stands a box made out of
light of plank not less than $1\frac{1}{4}$ inch thick of wood proper for such purpose, 18 to 24
inches square and 10 to 12 inches deep. The box and frame to be made of an equal
size. Two blocks of equal size of plank of not less than $1\frac{1}{4}$ inches thick of a size
to cover the bottom of the box inside to within half an inch on each side and allow-
ing the beaten to leave such space. Wooded bars to be attached across the beaten

The bars to be 1 $\frac{1}{2}$ inches deep $1\frac{1}{4}$ inches wide
and be attached to the bottom of the beaten, and bevelled to half an inch wide on the
bottom, calculated when the beaten are pressed down to fit closely between similar
bars fastened on the bottom of the box inside. Two upright shafts 18 to 24 inches
long & $\frac{1}{2}$ inches thick and two inches wide to be framed into each beaten near the
ends. The cover to the box to be made of a panel one inch thick surrounded with
a frame of hard wood composed of pieces $1\frac{1}{2}$ to 2 inches square with mortises $\frac{3}{4}$
inches wide and 8 inches long made to correspond with the position of the upright
shaft to frame to the beaten and allowing said shaft to go through. The cover to
be made tight to the top of the box and to be attached thereto with substantial
braces on one side and proper fastenings on the other side, to keep the frame from
